[57] CLAIM

The ornamental design for a front and side panels of a desk, substantially as shown and described.

DESCRIPTION

FIG. 1 is a front elevational view of the front and side panels of a desk showing my new design;

FIG. 2 is a perspective view thereof; and

FIG. 3 is a side elevational view thereof.

The partial shading on the panels indicates fabric.

FIG. 1

FIG. 2

FIG. 3
